(57) **CLAIM**

The ornamental design for a handle for a medical delivery device, as shown and described.

DESCRIPTION

FIG. 1 is a left and top perspective view of a handle for a medical delivery device showing our new design;

FIG. 2 is a front view thereof;

FIG. 3 is a rear view thereof;

FIG. 4 is a left side view, the right side view being a mirror image thereof;

FIG. 5 is a top plan view thereof; and,

FIG. 6 is a bottom plan view thereof.

Portions in the figures that are in broken line are intended to show environmental structure or boundaries, and therefore form no part of the design to be patented.
